United States Patent Office

Des. 203,808
Patented Feb. 22, 1966

203,808

VACUUM CLEANER

Robert C. Lagerstrom, Normal, and Joseph R. Mango,
Midlothian, Ill., assignors to National Union Electric
Corporation, Stamford, Conn., a corporation of Delaware

Filed June 26, 1964, Ser. No. 80,598

Term of patent 14 years

(Cl. D9—2)

FIG. 1 is a reduced perspective view of a hand vacuum cleaner, showing our new design;

FIG. 2 is a top plan view;

FIGS. 3 and 4 are front and rear end views, respectively;

FIG. 5 is a side view; and

FIG. 6 is a bottom plan view of the cleaner.

The dominant features of our design are shown in full lines.

We claim:

The ornamental design for a vacuum cleaner, substantially as shown and described.
